United States Patent Office.

SAMUEL D. VOSE, OF MILWAUKEE, WISCONSIN.

Letters Patent No. 92,674, dated July 13, 1869.

STOVE-COVER.

The Schedule referred to in these Letters Patent and making part of the same.

To all whom it may concern:

Be it known that I, SAMUEL D. VOSE, of the city and county of Milwaukee, and State of Wisconsin, have invented a new and improved Method of Constructing Stove-Covers; and I do hereby declare the following is a full and exact description of the same, reference being had to the accompanying drawings, and to the letters of reference marked thereon.

Figure 1 is a plan of the top of the cover.

Figure 2 is a vertical section of the cover through the line A A, in fig. 1.

To enable others skilled in the art to make and use my invention, I proceed to describe it.

The cover is made in two pieces.

The plate B is a cast-iron ring, on the inside edge of which is a recess, to receive a smaller round plate of cast-iron, plate O.

Holes, to correspond, are cast in each plate, and two rivets, R, are used to join them together.

If covers of an unusual size are required, the use of three or more pieces may be of advantage.

The joining may be effected by rivets, or by projecting wedges dropped through slots, and binding under the flange or in other ways.

The usefulness of this method is the security obtained against warping and cracking; also, in a reduction of the weight and cost.

The plate O is too small to have an unequal expansion or to droop. The plate B, being in the form of a narrow ring, with edges strengthened on the in-

side and outside, the ring expands and contracts equally. For the same reason this ring is not subject to warping.

A very thin cover thus made will keep whole longer and outwear a solid one of greatly increased thickness.

The break between the plates O and B lessens, by a quicker radiation, the intensity or redness of heat, which is so destructive to a solid cover.

I am aware that rings have been used to contract the size of boiler holes. Large boiler holes have been supplied with several contracting rings to suit culinary vessels of different sizes, but the solid cover has always filled up the smallest ring.

I am also aware that plates of cast-iron, of large surface, have been divided and subdivided in various ways to overcome unequal expansion, but not in this manner.

What I claim as my invention, and desire to secure by Letters Patent, is—

The method of constructing a cover for stoves, by making the outer part B in the form of a ring, and the inner part O in the form of a separate circular plate, capable of expanding and contracting by itself, these parts being riveted or connected so as to form, when finished, a portable cover, as herein described.
